(57) **CLAIM**

The ornamental design for a battery as shown and described.

DESCRIPTION

FIG. 1.1 is a top, front, and right side perspective view of a battery according to a first embodiment of our new design; FIG. 1.2 is a front elevational view thereof; FIG. 1.3 is a rear elevational view thereof; FIG. 1.4 is a left side elevational view thereof; FIG. 1.5 is a right side elevational view thereof; FIG. 1.6 is a top plan view thereof; FIG. 1.7 is a bottom plan view thereof; FIG. 5.1 is a top, front, and right side perspective view of a battery according to a second embodiment of our new design; FIG. 5.2 is a front elevational view thereof; FIG. 5.3 is a rear elevational view thereof; FIG. 5.4 is a left side elevational view thereof; FIG. 5.5 is a right side elevational view thereof; FIG. 5.6 is a top plan view thereof; FIG. 5.7 is a bottom plan view thereof; FIG. 5.8 is an enlarged view of FIG. 5.6; FIG. 8.1 is a top, rear, and right side perspective view of a battery according to a third embodiment of our new design; FIG. 8.2 is a bottom, front, and right side perspective view thereof; FIG. 8.3 is a front elevational view thereof; FIG. 8.4 is a rear elevational view thereof; FIG. 8.5 is a left side elevational view thereof; FIG. 8.6 is a right side elevational view thereof; FIG. 8.7 is a top plan view thereof; FIG. 8.8 is a bottom plan view thereof; and

(Continued)

FIG. 8.9 is an enlarged view of FIG. 8.7.
The broken lines in the drawings depict portions of the battery that form no part of the claimed design.
